(57) **CLAIM**

I claim the ornamental design for a sash lock housing, as shown and described.

DESCRIPTION

FIG. 1 is a perspective view of a sash lock housing showing my new design;

FIG. 2 is a top plan view thereof;

FIG. 3 is a right side elevational view thereof, the left side elevational view being a mirror image thereof;

FIG. 4 is a front elevational view thereof; and,

FIG. 5 is a rear elevational view thereof.

The broken lines, which define the bounds of the claimed design, form no part thereof.

The broken lines showing environment are for illustrative purpose only and form no part of the claim design.
